UNITED STATES PATENT OFFICE.

CYRUS E. MOREHOUSE, OF MILWAUKEE, WISCONSIN.

BINDER.

1,250,203.

Specification of Letters Patent. Patented Dec. 18, 1917.

Application filed February 9, 1917. Serial No. 147,632.

To all whom it may concern:

Be it known that I, CYRUS E. MOREHOUSE, a citizen of the United States, residing at Milwaukee, county of Milwaukee, 5 State of Wisconsin, have invented certain new and useful Improvements in Binders, of which the following is a specification.

This invention relates to improvements in binders.

10 The main objects of this invention are:

First, to provide an improved binder which effectively binds and supports the sheets and at the same time permits them to lie quite flat when the binder is open.

15 Second, to provide an improved binder in which the binding members automatically adjust themselves as the binder is opened and closed.

Third, to provide an improved binder 20 having these advantages in which the sheets may be quickly inserted or removed.

Fourth, to provide an improved binder having these advantages which is simple and economical and at the same time strong and 25 durable in structure.

Further objects, and objects relating to structural details, will definitely appear from the detailed description to follow.

I accomplish the objects of my invention 30 by the devices and means described in the following specification. The invention is clearly defined and pointed out in the claims.

A structure which is a preferred embodiment of my invention is clearly illustrated 35 in the accompanying drawing, forming a part of this specification, in which:

Figure I is a detail longitudinal section through a binder embodying the features of my invention with the binder in its closed 40 position and the sheets therein, taken on a line corresponding to line 1—1 of Fig. III.

Fig. II is a detail section taken on a similar line with the binder open and a portion 45 of the sheets resting on each cover.

Fig. III is a detail plan view of the inside of the binder with the covers extended, the extended position of the binding members being indicated by dotted lines.

50 Fig. IV is an enlarged detail section on a line corresponding to line 4—4 of Figs. I and VI, showing structural details.

Fig. V is a transverse section through one 55 of the binding members on a line corresponding to line 5—5 of Fig. II.

Fig. VI is a detail section on a line corresponding to line 6—6 of Fig. III.

Fig. VII is a detail inside view, similar to that of Fig. III, of another embodiment of my invention.

Fig. VIII is a detail section on a line corresponding to line 8—8 of Fig. VII, with the binding member collapsed or retracted.

Fig. IX is a similar detail section with the binding member extended.

In the drawing similar reference characters refer to similar parts throughout the several views, and the sectional views are taken looking in the direction of the little arrows at the ends of the section lines.

Referring to the drawing, the back 1 is preferably formed of sheet metal having knuckles 2 formed on each longitudinal edge. The covers 3 have a hinge connection with the back, the connection preferably being formed by the facing or covering 4 which is continuous on the back and covers. The sheets 5 are perforated to receive the binding members which are, in the preferred embodiment illustrated, formed of a pair of telescoping sections 6 and 7. The section 6 is adapted to receive the section 7. The binding member sections have eyes or knuckles 8 at their outer ends. These binding members are supported by links 9 which have knuckles 10 at their inner ends and knuckles 11 at their outer ends. These links 9 are preferably formed of sheet metal, the knuckles being formed by rolling up the ends. These knuckles are oppositely disposed, that is, the knuckles 10 are disposed at the outer sides of the links, while the knuckles 11 are disposed at their inner sides. This permits a greater opening or extending movement than would be the case if the 95 knuckles were reversed or disposed in alignment with the bodies of the links.

The links are secured to the covers by the pintles 12 arranged through the knuckles on the back to engage the knuckles 10 of the 100 links. They are secured to the ends of the binding members by the pintles 13 arranged through the knuckles 11 of the link to engage the knuckles 8 on the ends of the binding members.

In the embodiment shown in Figs. I, II and III, these pintles 13 are continuous, that is, a single pintle connects all of the binding members at one end. Any desired number of binding members may be employed, the 110

number being varied according to the size of the binder.

In the embodiments shown in Figs. VII, VIII and IX, the binding members are formed of three sections, there being a central tubular section 14 and end sections 15 having telescoping engagement therewith. The end sections are provided with eyes or knuckles to receive the pintles 16 which are, 10 in this embodiment, short pintles, that is, they are not common to all of the binding members.

The embodiment shown in Figs. I, II and III, is, however, more simple and I find, 15 very satisfactory.

With this arrangement of parts, the binding members are free to extend or collapse as the binder and the sheets therein are opened and closed. The binding members 20 extend, when the binder is opened, and allow the sheets to lie quite flat and they automatically retract when the binder is closed. The sheets are effectively held by these binding members so that they do not sag or get 25 out of alignment when the binder is handled.

My improved binder is especially desirable for use as a catalogue binder or the like, as catalogues are held very securely therein and at the same time are fully accessible for inspection.

The structure has the further advantage of being capable of easy and quick manipulation for the insertion and removal of sheets and also the parts are simple and economical to 35 produce and assemble. I have not attempted to maintain the relative proportion of the parts in the accompanying drawing, various sheet metal parts being shown as quite thick in the interest of clearness.

40 I have used the term sheets in its broad sense, as the binder is, as stated, well adapted for the holding of catalogues, pamphlets and the like.

I have illustrated and described my improvements in the form in which I have embodied the same for the market. I have not attempted to illustrate or describe certain modifications in structural details which I contemplate, as I believe the disclosure made 50 will enable those skilled in the art to which my invention relates to adapt the same to the particular requirements or purposes for which the binder is intended.

Having thus described my invention, what 55 I claim as new and desire to secure by Letters Patent, is:

1. In a binder, the combination of a back, binding members comprising sections having telescoping engagement and provided 60 with knuckles, links having oppositely disposed knuckles at their ends, the knuckles at the inner ends of the links being disposed on

the outer side, link supporting pintles carried by said back, and pintles connecting said links to said binding members. 65

2. In a binder, the combination of a back, binding members comprising sections having telescoping engagement and provided with knuckles, links having knuckles at their ends, link-supporting pintles carried 70 by said back, and pintles connecting said links to said binding members.

3. In a binder, the combination of a back, covers having hinge connection thereto, telescoping binding members, and links mounted 75 on said back and connected to the ends of said binding members permitting them to extend and collapse for the purpose specified.

4. In a binder, the combination of a back, 80 freely slideable telescoping binding members, and links mounted on said back and connected to the ends of said binding members permitting them to extend and collapse, for the purpose specified.

5. In a binder, the combination of a back, covers hinged thereto, an extensible binding member, and link connections for connecting said binding member to said back permitting it to extend and retract, for the purpose specified. 90

6. In a binder, the combination of a back, a binding member, and link connections for connecting said binding member to said back permitting it to extend and retract 95 upon the opening and closing of the binder, for the purpose specified.

7. In a binder, the combination of a back, covers having hinge connections therewith, sheets perforated to receive binding 100 members, binding members comprising telescoping sections disposed through such perforations, and links pivotally mounted on said back and pivotally connected to said binding members permitting the extension 105 and collapsing thereof as the binder and sheets are opened and closed.

8. In a binder, the combination of a back, covers having hinge connections therewith, sheets perforated to receive binding members, extensible binding members disposed through such perforations, and links pivotally mounted on said back and pivotally connected to said binding members permitting the extension and retraction thereof, as 110 the binder and sheets are opened and closed. 115

In witness whereof, I have hereunto set my hand and seal in the presence of two witnesses.

CYRUS E. MOREHOUSE. [L.S.]
